UNITED STATES PATENT OFFICE

JOHN I. W. CARLSON, OF SCOTTDALE, PENNSYLVANIA

LOCK

Application filed June 16, 1931. Serial No. 544,847.

This invention relates to locks, and has for its object the production of a simple and efficient lock which may be opened by either a combination means or a key.

Another object of this invention is the production of a simple and efficient lock specially constructed so as to permit the operation of the lock either by a key, or by the manipulation of a desired combination means, whereby the locking bolt and bolt casing may be shifted bodily within the lock casing, by turning the door knob.

Another object of this invention is the production of a simple and efficient lock consisting of a minimum number of parts and which may be manufactured at a minimum cost.

With these and other objects in view, this invention consists of certain novel constructions, combinations and arrangements of parts as will be hereinafter fully described and claimed.

In the drawings:

Figure 1 is a front elevation of the lock showing the graduated combination discs, the key lock and relative location of the knob handle;

Figure 2 is a vertical sectional view through the lock casing, certain portions of the locking mechanism being shown in side elevation, the locking mechanism being shown in a locked position;

Figure 3 is a similar view to Figure 2, the locking bolt and locking casing being shown in an unlocked position;

Figure 4 is a transverse sectional view taken on lines 4—4 of Figure 2;

Figure 5 is a section taken on line 5—5 of Figure 3;

Figure 6 is a section taken on line 6—6 of Figure 2;

Figure 7 is a section taken on line 7—7 of Figure 2;

Figure 8 is a perspective view of the bolt casing, a portion of the face plate being shown in section; and

Figure 9 is a perspective view of one of the tumbler discs used in connection with the combination lock.

By referring to the drawings, it will be seen that 1 designates the lock casing which

may be placed in any desired or convenient position upon the door, the casing being either placed in one side of the door or mitered therein without departing from the spirit of the invention. The casing 1 is provided with a cover plate 2, which casing may be secured in any suitable or desired means to the casing 1, such for instance as by means of the screws 3. The usual keeper 4 is carried by the door jamb 5, and is provided with a socket 6 for the purpose of receiving the locking bolt 7.

The locking bolt frame 8 supports the locking bolt 7, which locking bolt 7 extends through the aperture 9 formed in one side edge of the casing 1, in alignment with the socket 6 so as to permit the bolt 7 to pass through the casing 1 and fit in the socket and hold the door 10 upon which the lock casing 1 is mounted in a locked position with respect to the door jamb 5. This bolt frame 8 is provided with a tumbler receiving pocket 11 formed therein which is normally closed by means of a cover plate 12. This cover plate may be secured in any suitable or desired manner to the bolt frame 8, such for instance, as by means of the screws 13.

The tumbler supporting shaft 14 is extended through the apertures 15 and 16 formed in the bolt frame 8 and cover plate 12 respectively, and this particular supporting shaft 14 is provided with an enlarged knob 17 formed at one end having a graduated disc 18, which knob 17 and graduated disc 18 fit upon the outer face of the face plate 2 of the lock casing 1, and facilitate the operation of the combination lock as is usual with devices of this type. The face plate is suitably marked by numerals or otherwise indicated to permit the operator to turn the disc to the desired position for the purpose of operating the lock. This tumbler supporting shaft 14 is provided with a longitudinally extending rib 19 which is adapted to engage suitable lugs 20 formed upon the periphery of the centrally located apertures 21 of the tumbler discs 22. Any suitable or desired number of tumbler discs 22 may be employed and by rotating the tumbler supporting shaft 14 in the desired direction and for the desired

distance, the tumbler discs 22 may be brought into proper position so as to cause the bolt receiving notches 23 thereof to be brought into registration in such a position as is shown in Figures 3 and 5 of the drawings. The shaft 14 carries at its opposite end a knob 19' to permit the operation of the shaft from the inside of the door.

The bolt housing or frame 8 is provided with a longitudinally extending notch 24 formed at the rear end thereof which is adapted to register with the notches 23 when the tumbler discs 22 are moved to the proper or desired position for the purpose of opening the lock. The bolt frame 8 is provided with a rearwardly extending ledge portion 25 upon which ledge portion 25 is adapted to rest the key actuated bolt 26 hereinafter described.

As shown in the drawings, the bolt frame 8 may be provided upon the lower face thereof or in any desired or convenient location with a plurality of closely arranged and spaced lugs 27, which lugs 27 are adapted to be engaged by a rollback 28 carried by the knob actuated cylinder 29, which cylinder 29 is carried by the squared shank 30 of usual door knob construction 31. The spring 32 is mounted within the casing 1 and normally engages one side of the rollback 28 and holds the same in a vertical position so as to normally urge the bolt frame 8 to a locked position such as is shown in Figure 2 of the drawings.

If it is so desired, this particular structure may be eliminated from the lock without departing from the spirit of the invention, but it has been found convenient and advisable to provide this construction just described to facilitate the operation of the lock through the medium of the door knob 31.

In order to permit the operation of the lock through the medium of the usual key and cylinder locking structure, there is provided a cylinder lock 32 of any suitable or desired type which is adapted to receive a key 33 for the purpose of permitting the rotation of the shaft 34, thereby permitting the swinging of the key operated bolt 26 to the position shown in full lines in Figure 2, or to the vertical position indicated by dotted lines in this figure out of the path of movement of the bolt frame 8. A suitable knob 35 is carried by the opposite end of the shaft 34 so as to permit the operation of the shaft from the inside of the door without the necessity of operating the key 33. This lock 32 may be, as stated above, of any suitable or desired type of the cylinder lock structure without departing from the spirit of the invention. The key operated bolt 26 is carried by a barrel 36 which is provided with a flat surface 37 upon one side, and an adjoining flat surface 38 arranged at right angles to the flat surface 37. A flat spring 39 is carried within the

casing 1 and is adapted to engage the respective flat surfaces 37 and 38 and permit the holding of the key controlled bolt 26 either in a horizontal or vertical position such as is shown in Figures 2 and 3 of the drawings and indicated by dotted lines in Figure 2.

From the foregoing, it will be seen that a very simple and efficient means has been produced for facilitating the operation of the lock either through the operation of the combination or tumbler discs, or through the operation of the key controlled bolt 26 by moving the controlled bolt 26 out of the path of movement of the bolt frame, this being accomplished through the operation of the key 33 within the cylinder lock 32. The cylinder lock 32 has only been indicated in a conventional manner, as any suitable or convenient or desired type of cylinder lock may be employed without departing from the spirit of the invention.

It should also be understood that certain detailed changes in the mechanical construction may be employed so long as these changes fall within the scope of the appended claims. It should be understood, however, that the present invention relates particularly to the type of lock which may be actuated through the operation of the key controlled bolt or through the operation of the tumbler discs by operating the proper combination provided for through the manipulation of the knob 17.

It should be further understood that when the tumbler discs are moved so as to have the notches 23 register with the notch 24 formed in the lock frame 8, the entire lock frame carrying the bolt 7 may be shifted longitudinally within the casing or frame 1, due to the fact that the tumbler supporting shaft 14 is slidably mounted within the longitudinally extending slots 40 formed in the frame or casing 1, and cover or face plate 2, the door 10 also being longitudinally slotted as indicated at 41 to permit the proper shifting of the shaft 14 longitudinally within the slots 40 and 41, which slots register as clearly shown in the drawings. As the bolt frame 8 is shifted longitudinally within the casing or frame 1, it will be seen that the key controlled bolt 26 may pass into the notches 23 and 24 due to the fact that this bolt normally rests upon the ledge 25.

The cylinder or barrel lock 32, as well as the knob 35, which permits of the operation of the key controlled bolt 26 on the inside of the door may be constructed in a similar manner to that as described in my co-pending application filed June 16, 1931, Serial Number 544,846, and relating to a combination and key controlled latching mechanism for locks.

When it is desired to operate the lock through the medium of a key, the key may be manipulated within the cylinder lock 32 so

as to cause the bolt 26 to extend in a vertical position such as is shown in dotted lines in Figure 2, whereupon the bolt 7 and frame 8 may be bodily moved longitudinally of the 5 slots 40 and 41, thereby drawing the bolt 7 out of the notch or pocket 6 of the keeper, in this way permitting the door to be swung to an open position. Furthermore, when the key controlled bolt 26 is in a position as 10 shown in dotted lines in Figure 2, the bolt frame 8 as well as the bolt 7 carried thereby may be readily moved to an open position by the operation of the knob merely by swinging the rollback 28 to the position 15 shown in Figure 3.

It should be understood that the present lock may be used upon any suitable or desired structure such as a door, drawer, or other device adapted to be locked, without 20 departing from the spirit of the invention.

Having described the invention, what is claimed as new is:

1. A lock for operation through the medium of a combination or a key comprising a 25 casing, a slidably mounted bolt frame, a tumbler supporting shaft passing through said bolt frame, tumbler discs mounted upon said shaft, means formed upon said tumbler shaft for turning said tumbler discs to a predetermined position, said discs provided with registering notches, said bolt frame provided with a notch adapted to register with said notches, a key controlled bolt rotatably mounted within said casing and adapted to 30 be brought into alignment with said notches, said key controlled bolt provided with a sleeve having flat surfaces upon the sides thereof, and a spring adapted to engage said flat surfaces for holding said key controlled 35 bolt in a set adjusted position.

2. A lock comprising a casing, a bolt frame 40 slidably mounted within said casing and formed with an opening within its periphery, tumbler disks within said bolt frame and having slots leading from their edges, means for turning said disks to dispose their slots in registry with each other and the opening in the bolt frame, means in said casing movable into and out of position to pass through the 45 opening in the bolt frame and enter the slots of the disks to permit shifting of said bolt frame to a retracted position, said bolt frame being provided with a pair of spaced lugs, a knob operated shaft, and a rollback carried 50 by said shaft and engaged between said lugs for causing shifting of said bolt frame to a retracted position as the shaft is turned.

3. A lock comprising a casing, a bolt frame 55 slidably mounted within said casing and formed with an opening in its periphery, tumbler disks within said bolt frame and having slots leading from their edges, means for turning said disks to dispose their slots in registry with each other and the opening in 60 the bolt frame, means in said casing movable

into and out of position to pass through the opening in the bolt frame and enter the slots of the disks to permit shifting of the bolt frame to a retracted position, and means for moving the bolt frame to its retracted position.

4. A lock comprising a bolt frame, a tumbler supporting shaft passing through said bolt frame, a casing having opposed walls provided with slots for receiving said shaft, means for rotating said shaft, means formed upon the shaft and disks for rotating the disks, an opening being formed in said bolt frame, said disks being provided with notches to be brought into registry with each other and the opening in the bolt frame when the disks are moved to a predetermined position, an auxiliary bolt movable into and out of alignment with the opening in said bolt frame whereby the bolt frame and disks may be shifted over the auxiliary bolt for moving the bolt frame to a retracted position, and means for releasably holding said auxiliary bolt in a set position.

5. A lock for operation through the medium of a combination or a key comprising a 90 casing, a slidably mounted bolt frame in said casing, a tumbler supporting shaft passing through the casing and bolt frame, tumbler disks upon said shaft and formed with 95 notches leading from their edges, means for moving the tumblers into position to dispose the notches in registry with each other, a key controlled bolt rotatably mounted within said casing and adapted to be brought into alignment with said notches and permit movement of the bolt frame to a retracted position, said key controlled bolt being provided with a sleeve having flat surfaces upon its sides and disposed transversely of each other, and a 100 spring to engage said flat surfaces for holding the key controlled bolt in a set position.

In testimony whereof I affix my signature.

JOHN I. W. CARLSON.
